US0D1075401S

(12) **United States Design Patent** (10) **Patent No.:** **US D1,075,401 S**
(45) **Date of Patent:** **** May 20, 2025**

(54) **BLENDER**

(71) Applicant: **SharkNinja Operating LLC**, Needham, MA (US)
(72) Inventor: **Trevor Dyment**, Boston, MA (US)
(73) Assignee: **SharkNinja Operating LLC**, Needham, MA (US)
(**) Term: **15 Years**
(21) Appl. No.: **29/898,827**
(22) Filed: **Aug. 1, 2023**

(51) **LOC (15) Cl.** 31-00
(52) **U.S. Cl.**
USPC **D7/413**

(58) **Field of Classification Search**

USPC D7/369, 370, 371, 372, 373, 376, 377, D7/378, 379, 380, 381, 382, 383, 384, D7/385, 386, 387, 412, 413, 414, 415, D7/669, 678, 679

(57) **CLAIM**

The ornamental design for a blender, as shown and described.

DESCRIPTION

FIG. 1 is a left perspective view of a blender, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The purpose of the broken lines shown in the drawings is to denote features of the structure that form no part of the claimed design.

1 Claim, 7 Drawing Sheets
